UNITED STATES PATENT OFFICE.

D. BERT HARTLEY, OF CHICAGO, ILLINOIS.

ROCKING, RECLINING, AND EASY CHAIR.

SPECIFICATION forming part of Letters Patent No. 276,687, dated May 1, 1883.

Application filed March 22, 1882. (No model.)

To all whom it may concern:

Be it known that I, D. BERT HARTLEY, of Chicago, in the county of Cook and State of Illinois, have invented certain new and useful 5 Improvements in a Combined Rocking, Reclining, and Easy Chair, of which the following is a full, clear, and exact description, that will enable others to make and use the same, reference being had to the accompanying drawings, and to the letters of reference marked thereon, forming a part of this specification.

This invention relates to improvements in that class of chairs which are adapted to be converted from an upright to a reclining position, and changed from an easy to a rocking chair, as may be desired; and it consists in the construction and arrangement of the parts, as will be hereinafter more fully set forth in detail.

Figure 1 is a side elevation of a chair embodying my improvement, the back being in a reclining position and the foot-rest extended. Fig. 2 is a side elevation, partially in section, with the back in an upright position and the 25 foot-rest folded underneath the chair-seat; Fig. 3, a detached top view of the foot-rest and sliding frame. Figs. 4, 5, 6, 7, 8, and 9 are detached details of construction.

Referring to the drawings, A represents the 30 back of the chair, A' the rocking members, and A² the supporting-base. The arms A³, supporting the head-rest A⁴, and the side arms, B, are connected by means of the ratchet-wheels a a', having the strap-extension a², as shown 35 in Fig. 5 of the drawings. These ratchet-wheels are placed on the inside of the arms, and are attached by means of the screws a³, which pass through the strap-extension a², as shown in Fig. 4 of the drawings. The joining 40 faces of these ratchet-wheels are provided with a series of teeth, and are adapted to engage with each other for the purpose of securing the head-rest at any point in the line of adjustment without reference to the inclination or position of the back of the chair proper. The ratchet-wheels are perforated for the 45 reception of the rod B', which passes clear through both sides of the chair and provides a pivotal bearing for these parts. The projecting ends of the rod B' are threaded for the 50 reception of the locking nut or nuts a⁴. By slackening up on the same the parts will spread just

enough to throw the ratchet-wheels out of engagement and allow the head-rest to be adjusted, as may be required, while by tightening 55 up on the same the head-rest is secured at any point. The lower end of the side arms, B, are pivoted to the short arms B², the lower ends of which are attached to the upper part of the rocking members. The wooden arms 60 B² are provided with the metallic connecting-arm b, which passes through the longitudinal center of the same, as shown in Fig. 7 of the drawings. The upper end of the arm b, projecting beyond the wood of the short arm B², 65 is incased in the lower end of the arm B. Upon the lower end of arm b is a ratchet-wheel, b', which abuts against the lower end of arm B², and is adapted to engage with the corresponding ratchet-wheel, b², embedded in the rocking 70 member or members A'. The ratchet-wheel b² is provided with the flange b³, having perforations b⁴ for the passage of attaching-screws, as shown in Fig. 8 of the drawings. These ratchet-wheels are provided with the shallow 75 recess B³, for the reception of the coiled spring B⁴, having the ends secured in the wheels, and as the same are rotated the tension on the spring is increased or diminished accordingly. This spring or springs serve to equalize the 80 weight of the bodies to which they are attached, and prevent the parts from dropping too suddenly when the ratchet-wheels are disengaged for the purpose of changing the back of the chair to a new position. Similar springs 85 are employed in the head-rest mechanism.

The rod C (shown in Fig. 6 of the drawings) extends through from side to side, and provides pivotal bearings for the ratchet-wheels as they are rotated in adjusting the back of 90 the chair. The eccentric end of the clamping-lever C' is slotted, so as to engage with the projecting end of the rod C, and is pivoted thereto, so as to be capable of being thrown up or down, as indicated in Fig. 6 of the drawings, in locking or unlocking these parts when adjusting the back of the chair.

The foot-rest D is adjusted by hand, and may be drawn out or pushed back underneath the chair-seat without the necessity of the occupant arising from the chair.

The sliding frame D' (shown in Fig. 3 of the drawings) forms a part of the foot-rest attachment, and fits in between the rocking mem-

bers. This sliding frame is provided with the bolts d d' d^2 d^3 , which have a sleeve or roller placed between the heads and the frame. These rollers are adapted to fit into the grooves D^2 (shown in Fig. 2 of the drawings) on the inside of the rocking members, which are curved to correspond to the circle of the rockers, the sliding frame D' being similarly curved. The staples d^4 , placed on the inside of the sliding frame D' , provide bearings through which move the unattached ends of the levers D^3 D^4 , the opposite ends being pivoted to the foot-rest D by means of the bolts F F' . The foot-rest D being pivoted to the frame D' by bolts F^2 F^3 , the levers D^3 D^4 rest and slide on the same as the foot-rest is adjusted. This arrangement forms a lever-hinge for the proper adjustment and support of the foot-rest.

The foot-rest D , as shown in Fig. 1 of the drawings, is drawn out to the farthest point, and by folding the same over, as indicated by the dotted lines, the rest is brought nearer to the chair, and is also in proper position to be pushed underneath the chair and out of the way when not required for use, as shown in Fig. 2 of the drawings. This foot-rest D is a hollow box having the top or cover f hinged thereto, and provided with a suitable fastening for securing the same, and is more especially intended as a receptacle for a boot-brush and blacking; but may be used as a receptacle for various articles.

The rocking members may be attached to the supporting-base by means of any of the various devices usually employed for this purpose, and when not required to be used as a rocking-chair the rocking members may be secured in a stationary position by means of the hooks E , (shown in Figs. 1 and 2 of the drawings,) the lower ends of which are pivoted to the supporting-base, while the upper or hooked ends are adapted to engage with eye-bolts inserted in the rocking members. By this arrangement the chair is adapted to be used as an easy, reclining, and rocking chair; or the same reclining mechanism and foot-rest attachment may be employed in connection with a chair constructed with legs instead of rocking members.

50 The clutch-box consisting of the ratchet-wheels and spring may be used with various other devices requiring mechanism of this nature, and particularly for the pivotal joints in buggy or carriage tops.

55 I am aware that chairs having their parts pivoted together to permit of a tilting movement, rods having a clamping-rod, and an adjusting cap or nut for holding parts together, ratchet-wheels meshing with each other, and 60 having a spring which forces them apart, and a cam-lever for drawing parts together, are all old, and to them I make no claim.

65 I make no specific claim in this application to the clutch mechanism, the foot-rest, and the device for locking the chair against rocking, as they will form the subject-matter of separate

Having thus described my invention, what I claim as new, and desire to secure by Letters Patent, is—

1. In a reclining-chair having its parts pivoted together, the combination, with one part thereof having a ratchet-wheel attached thereto, of a second part having attached thereto a ratchet-wheel corresponding to, on the same shaft as, and facing the other ratchet-wheel, a spring interposed between and having its ends attached to the opposite faces of said wheels to prevent the parts from dropping when unclamped, and a device for clamping the parts together, substantially as described. 75

2. The combination of a chair-seat having a ratchet-wheel on each side, a back pivoted to said seat, arm-rests pivoted to the back and seat, and each having a ratchet-wheel which 85 meshes with the ratchet-wheels on the seat, a spring interposed between and attached to the opposite faces of said ratchet-wheels to prevent the parts from dropping when unclamped, and a clamping device, substantially as de- 90

95 3. The combination of a chair-seat having a ratchet on each side, a back pivoted to said seat, arm-rests pivoted to the back and seat, and each having a ratchet-wheel at both ends, a head-rest pivoted to the back and arm-rests, and having a ratchet-wheel on each side to mesh with the ratchet-wheels upon the upper end of the arm-rests, and clamping devices which draw the seat and arm-rests, and the 100 arm-rests, back, and head-rests together, substantially as described.

105 4. The combination of a chair-seat having a ratchet on each side, a back pivoted to said seat, arm-rests pivoted to the back and seat, and each having a ratchet-wheel at both ends, a rod passing through both sides of the seat, serving as bearings for the ratchet-wheels, and having an eccentric clamping-lever, a head-rest pivoted to the back and arm-rests, and having a ratchet-wheel on each side to mesh with the ratchet-wheels upon the upper end of the arm-rests, and a rod extending through the back, arms, and head-rest, and having a clamping device on one end, for the purpose 110 115 set forth.

5. In a rocking and reclining chair, the back A , in combination with the arm-rests B , the arm B^2 , the metallic connecting-arm b , having the ratchet-wheel b' , formed integral therewith, 120 the ratchet-wheel b^2 , the rocking member A' , and the rod C , substantially as described.

6. The combination, with the back A , of the head-rest arms A^3 , and the arm-rests B , the ratchet-wheels a a' , provided with the strap-extension a^2 , the rod B' , and the clamping-nut a^4 , substantially as described. 125

D. BERT HARTLEY.
